UNITED STATES PATENT OFFICE.

NELIUS JULIAN NESSA, OF SIOUX FALLS, SOUTH DAKOTA.

INDICATING APPARATUS.

1,168,957.

Specification of Letters Patent. Patented Jan. 18, 1916.

Application filed September 9, 1914. Serial No. 860,924.

To all whom it may concern:

Be it known that I, NELIUS J. NESSA, a citizen of the United States, residing at Sioux Falls, in the county of Minnehaha and 5 State of South Dakota, have invented new and useful Improvements in Indicating Apparatus, of which the following is a specification.

This invention relates to certain novel and 10 useful improvements in fluid operated circuit closers.

In carrying out the present invention it is my purpose to provide a circuit closer which may be used in conjunction with a 15 liquid containing tank or receptacle to indicate the level of the liquid therein, and wherein the component parts will be so arranged and correlated as to reduce the possibility of derangement to a minimum.

20 With the above and other objects in view, the invention consists in the construction, combination and arrangement of parts hereinafter set forth in and falling within the scope of the claims.

25 In the accompanying drawings, Figure 1 is a vertical sectional view through the circuit closer constructed in accordance with my present invention. Fig. 2 is a cross sectional view on the line 3—3 of Fig. 1. Fig. 30 3 is a fragmentary vertical sectional view on the line 4—4 of Fig. 2.

Referring now to the drawings in detail, A designates a fluid controlled device comprising a circular disk 1 formed centrally 35 with an aperture in which is rotatably mounted a pin 2 formed with an annular flange 3 engaging the upper surface of the disk 1 and an annular flange 4 engaging the lower surface of the disk and coacting with 40 the flange 3 to hold the pin against longitudinal movement. Fastened to the lower end of the pin 2 in some suitable manner and projecting downwardly therefrom and coaxial therewith is a shaft 5 capable of rotation

45 and formed with a longitudinally extending spiral groove 6 extending around one-half the circumference of the shaft and of a length equal to that of the shaft. Secured to the under surface of the disk and 50 depending therefrom and spaced apart equal distances about the shaft 5 are guide rods 7, while arranged concentrically of the shaft and capable of vertical sliding movement along the same is a float 8 constructed of 55 suitable material and having the periphery thereof equipped with eyes 9 through which

the rods 7 pass. Fastened to the upper surface of the float 8 is a tooth 10 projecting toward the axis of the float and engaged in the groove 6 in the shaft 5 so that as the 60 float moves vertically along the shaft the latter will be revolved. In the vertical sliding movement of the float the rods 7 hold the same against rotation so that the shaft will revolve under the action of the tooth. The 65 disk 1 is preferably composed of insulating material and embedded in the upper surface thereof concentrically of the axis of the disk is a collector ring 11. Arranged concentrically of the ring 11 is a semicircular row of 70 segments 13 spaced apart equal distances. Fixed to the upper extremity of the pin 2 and adapted to rotate therewith under the action of the shaft 5 is a bridging finger 14 spanning the collector ring 11 and the row 75 of contacts 13.

In practice, the fluid controlled device A is disposed vertically within a tank or receptacle and the tank filled to the desired point. As the liquid flows into the tank 80 the float 8 of the device 8 rises and in the upward movement of the float the shaft 5 rotates thereby revolving the pin 2 and finger 14 so that the latter may move over the collector ring 11 and row of contacts 13 to 85 a point indicative of the quantity of liquid within the tank or receptacle. As the level of the liquid within the tank falls the float 8 moves downwardly and rotates the shaft 5 to carry the finger 14 over the collector 90 ring and row of contacts 13 in the reverse direction thereby indicating the discharge of liquid from the tank and the amount of liquid therein. The row of contacts 13 and the collector ring 11 may form the terminals 95 of an electric circuit including an indicating device rotatable in the movement of the finger 14 to indicate the quantity of liquid within the tank.

I claim:

1. A circuit closer comprising a disk of 100 insulating material formed centrally with an opening, a pin rotatably mounted within said opening and having the upper and lower ends thereof flanged to hold the pin 105 against longitudinal movement within the opening, a collector ring on one face of said disk concentrically of the opening therein, an annular row of contacts on said face of the disk concentrically of said ring, a finger 110 carried by said pin and rotatable therewith and bridging said contacts and ring, a shaft

secured to said pin and depending therefrom and having a longitudinally extending spiral groove formed therein, a float slidably mounted upon said shaft and capable of vertical movement along the shaft, and a tooth on said float engaging in said groove to rotate said shaft in the movement of the float.

2. A circuit closer comprising a disk of insulating material formed centrally with 10 an opening, a pin rotatably mounted within said opening and having the upper and lower ends thereof flanged to hold the pin against longitudinal movement within the opening, a collector ring on one face of said 15 disk concentrically of the opening therein, an annular row of contacts on said face of the disk concentrically of said ring, a finger carried by said pin and rotatable therewith

and bridging said contacts and ring, a shaft secured to said pin and depending therefrom and having a longitudinally extending spiral groove formed therein, a float slidably mounted upon said rod and capable of vertical movement along the rod, a tooth on said float engaging in said groove to rotate 25 said shaft in the movement of the float, guide rods depending from said disk and disposed adjacent to the outer edge of said float, and wires carried by the outer edge of said float and engaging said guide rods. 30

In testimony whereof I affix my signature in presence of two witnesses.

NELIUS JULIAN NESSA.
